To all whom it may concern:

Be it known that we, Constance R. Denoy and Helen Brenner Cuny, both citizens of the United States, both residing at Cliffside Park, in the county of Bergen and State of New Jersey, have invented a new, original, and ornamental Design for a Savings Bank, of which the following is a specification, reference being had to the accompanying drawing, forming a part thereof.

In the drawing:

Fig. 1 is a front perspective view of a savings bank showing our new design; and

Fig. 2 is a rear elevational view of the same.

We claim:

The ornamental design for a savings bank, as shown,

CONSTANCE R. DENOY.
HELEN BRENNER CUNY.
